UNITED STATES PATENT OFFICE.

WILMA M. PAIGE, OF JOPLIN, MISSOURI.

DESIGN FOR A BOOTH.

Application filed June 5, 1925. Serial No. 13,682. Term of patent 14 years.

To all whom it may concern:

Be it known that I, WILMA M. PAIGE, a citizen of the United States, residing at Joplin, in the county of Jasper and State of Missouri, have invented a new, original, and ornamental Design for a Booth, of which the following is a specification, reference being had to the accompanying drawing, forming a part thereof.

Fig. 2 is another side view of the booth taken from a point between the two doors, and showing the windows located in one side thereof and between the doors.

The design shown is manufactured and sold as a complete article.

I claim:

The ornamental design for a booth substantially as shown.

WILMA M. PAIGE.
